DICTATING MACHINE SIGNAL

Albert I. Kegan, Chicago, Ill., assignor to Samuel W. Kipnis, trustee for Judith Kegan, Daniel Kegan, and Franklin Kegan

Application November 27, 1948, Serial No. 62,380

5 Claims. (Cl. 274—1)

1

The present invention relates to methods of indexing directly upon dictating machine records, and to apparatus for this purpose.

Heretofore it was impossible to edit a dictated record either at rest or while running so as to audibly warn the transcribing typist before she heard the message she was to be warned about. Instead, the editing indicia were usually placed on a separate sheet of paper, sometimes by writing directly thereon, and sometimes by manually actuating apparatus which marked the paper. In either event, it was attempted to correlate very closely the position of the signal on the paper and the corresponding message on the record. Dictating machines wherein the position of the marking element relative to the paper is controlled by the position of the cutting head relative to the sound record, are used in conjunction with transcribing machines wherein the markings on the paper are read by means of a pointer, the position of which relative to the paper is controlled by the position of the transcribing head relative to the sound record. However, inevitable deviations between the dictating machine and the transcribing machine prevent exact correlation between any given portion of the sound track and the corresponding signal on the paper. Mechanical slack, errors in calibration, etc., in the correlating mechanism in the dictating machines further increase the deviation between the two, which again is aggravated by similar defects in the transcribing machine. In addition, there is the human error in observing the precise position of the mark on the paper relative to the index therefor. All these factors combine to make indexing systems extraneous to the sound record itself unreliable, and their use exasperating and time-wasting to the transcriber. Moreover, since the warning approximately coincides with the subject matter thereof, the typist frequently transcribes matter before being warned that it is not to be typed as dictated.

Since the typist hitherto did not hear the warning signal through the same earphones through which she listened to the dictation, she was forced to watch expectantly for an additional, extraneous signal, so that her attention, already well occupied with operating both her typewriter and her transcribing machine while listening to the recorded dictation, was further divided and distracted by the tension-producing chore of constantly and expectantly watching the paper bearing the editing signals.

Another disadvantage of the previously known 55

2

indexing systems is that the index sheet, being separate from its corresponding sound record, is easily misplaced, lost or mismatched with the wrong record, all to the exasperation and waste of time of the typist.

Moreover, the paper index requires as much handling as the sound record blank, thus doubling the work both for the dictator and for the typist. The separate paper index requires 10 four additional operations: (1) accurately positioning it in the dictating machine, (2) removing it therefrom, (3) accurately placing it in the transcribing machine, and (4) removing it therefrom. An error of only 0.01 inch in positioning 15 the paper index results in a variation in indexing of about twenty spoken words in one of the most precise commercial makes of dictating machines. Thus it is apparent that really reliable indexing cannot be obtained in systems where 20 the indexing is not on the sound record itself.

It is a broad object of my invention, therefore, to overcome the disadvantages of the prior art indexing systems by providing methods of and apparatus for incorporating indexing signals 25 directly into the sound track of the dictation recording medium.

Another important object is to provide novel methods of, and apparatus for, creating, mechanically and otherwise than by sound or a sound-translating device, indentations in a record, which indentations generate an audible signal when said record is played through a conventional sound-reproducing head.

Yet another important object is to provide 35 methods of and apparatus for indexing any desired portion of the dictation so that upon transcription the transcriber is alerted by a characteristic audible warning signal before she hears the portion of the dictation which she is to alter.

Another object of my invention is to provide 40 novel methods of and apparatus for superposing a signal upon a recorded message in such manner that the signal does not interfere with the accurate transcription of any portion of said message.

Still another object is to provide novel apparatus which uniformly indexes a recorded message with great accuracy.

Yet another object is to provide apparatus 50 which places an alerting signal in the sound track a predetermined, definite, uniform time interval in advance of the event to which the signal relates.

By the term "trace," as used in the specification and claims, I mean any alteration in the

recording medium which generates an audible, characteristic signal when the record is played. By the noun "record" I mean the phonograph disk, cylinder, belt or other physical object which receives the sound track.

My novel method in its broad aspect comprises placing directly upon a record a trace which is reproducible as sound, yet which permits the recorded message upon which it is superimposed to be heard clearly. Said trace is placed on the record after the dictation to which it relates, but is heard on transcription before the transcriber hears the message to which it relates.

When the executive desires to correct the words he has just spoken, he merely presses the button of the signal control means, thereby imposing the signal trace upon the record itself, and then immediately dictates the correction. Or, if when listening back to his dictation, the executive decides to edit the same by inserting new matter, or by deleting, or by rephrasing, he simply actuates the operating key just as he hears the text where the change is to be made, thereby imposing a signal upon the record which the transcriber reaches and hears before she comes to the text which is to be edited. The dictator then moves the recording head to the end of the cut sound track upon the record and dictates the desired insertion, directions, or new material. The position on the record of the beginning of the additional editorial dictation may be indicated in the conventional way by a mark upon the paper tape; or by explanatory words dictated into the machine, or by both. The important feature is that the audible signal on the record warns the transcribing stenographer to stop typing before she comes to the material which requires revision.

In order that my invention may be more fully disclosed, reference is had to the accompanying drawings which exemplify several forms of apparatus for carrying out my novel method, and which embody the foregoing and such other principles, advantages or capabilities as may be pointed out as this description proceeds, or as are inherent in the present invention. For purposes of clarity in exposition, the following description is explicit, and the accompanying drawings are detailed, but it is distinctly to be understood that said exposition is illustrative only, and that my invention is not restricted to the particular details of operation or structure recited in the specification or shown in the drawings.

In the drawings:

Figure 1 is a side elevational view of a marking wheel and associated elements of an embodiment of my invention which utilizes a rolling marking member, shown installed upon a dictating machine having a stationary recording stylus past which the record is translated laterally while rotating, the marking member being shown in the disengaged position;

Figure 2 is a side elevational view of the device of Figure 1 with the marking member operating upon the record;

Figure 3 is a fragmentary front elevational view taken in section upon line 3-3 of Figure 1;

Figure 4 is a plan view taken in section on line 4-4 of Figure 2;

Figure 5 is a front elevational view of the device shown in Figure 2;

Figure 6 is a side elevational view of a second embodiment of my invention, which utilizes a reciprocating marking member, and is illustrated

as applied to dictating machines of the type shown in Figures 1-5;

Figure 7 is a plan view taken in section on line 7-7 of Figure 6;

Figure 8 is a fragmentary front elevational view of the embodiment of Figure 6;

Figure 9 is a detailed fragmentary perspective view of the reciprocating marking member of the embodiment of Figures 6-8;

Figure 10 is a fragmentary front elevational view of a third embodiment of my invention, as adapted for use with a dictating machine having a laterally moving stylus and rotating barrel-type record;

Figure 11 is a side elevational view of the embodiment of Figure 10;

Figure 12 is a detail front elevational view of the embodiment of Figure 10, with some parts broken away, and with the electrical circuit portion shown schematically;

Figure 13 is a somewhat schematic view of a fourth embodiment of my invention, illustrated in combination with a dictating machine wherein a recording and/or reproducing head translates radially across a disk type record which rotates about a laterally stationary axis;

Figure 14 is a side elevational view of a fifth embodiment of my invention in the disengaged or null position;

Figure 15 is a front elevational view of the embodiment of Figure 14;

Figure 17 is a side elevational view showing the mechanism of Figure 14 just prior to reciprocation of the marking member;

Figure 18 is a detail of the detent mechanism of the device of Figure 14, for forcing arm 96 downwardly upon rotation of arm 91;

Figure 19 is a front elevational view of a sixth embodiment of my invention, illustrated as part of a dictating machine wherein the recording and playback heads move laterally across an endless belt record which turns at right angles to the direction of movement of said heads;

Figure 20 is a side elevational view taken in section on line 20-20 of Figure 19;

Figure 21 is a detail rear elevational view taken in section on line 21-21 of Figure 20;

Figure 22 is a fragmentary side elevational view of a seventh embodiment of my invention, as adapted to mark upon a stationary record;

Figure 23 is a front elevational view taken in section on line 23-23 of Figure 22; and

Figure 24 is a detail plan elevational view taken in section on line 24-24 of Figure 23.

Like reference numerals refer to like parts in the drawings and in the description which follows.

Referring more particularly to the drawings, Figures 1-5 illustrate one form of apparatus for effectuating the methods of the present invention, said apparatus being shown upon a dictating machine of the type described in Proctor et al. Patent No. 2,296,870, issued September 29, 1942, and entitled Sound Recording and Reproducing. In this machine, the record 20 both rotates and translates laterally past the stylus 36 of the unit 35, which unit may be either a reproducing or a recording head. In normal operation, the record 20 is driven by a pair of cooperating friction rollers 33 and 34 (best shown in Figures 1 and 3). Said record 20 drives the spindle 32, about which said record revolves. The

wheel 37 supports the portion of the record 20 upon which the stylus 36 is acting.

The marking device of Figures 1-5 is also driven by the rotation of the record 20. Said device includes a friction drive wheel 31 having a surface of rubber or other material which will not skid appreciably on contact with the moving record surface 20. Said drive wheel 31 turns on shaft 22, which also carries the multi-tooth marking wheel 21. Said marking wheel 21 is keyed to the drive wheel 31, and is driven partly thereby and partly by engagement of its teeth with the record 20. The shaft 22 is carried at one end of the yoke 23. The other end of said yoke 23 is pivoted on the shaft 24, which projects through the bracket 25. A spring 26 acts to pull the yoke 23 upwardly, and thus lift the marking wheel 21 away from the record 20. Because of the action of the spring 26, the wheel 21 is normally disengaged from the surface of the record 20. To engage the wheel 21 with the record 20, the operator depresses the button 27 of the flexible Bowden wire 28 (see Figure 2), thereby moving the member 29 downwardly, which depresses the yoke 23 against the restraint of the spring 26. As the yoke 23 moves downward, the friction drive wheel 31 carried by the shaft 22 engages the surface of the record 20, and such engagement continues until the button 27 is released. The adjustable micrometer screw 30 acts as a stop to limit the downward travel of the yoke 23 so that the points on the wheel 21 will penetrate the surface of the record 20 only the desired amount. The friction drive wheel 31 also serves to limit downward movement of the wheel 21.

For the greater convenience of the dictator, the button 27 may be placed upon the hand microphone 15 customarily used with dictating machines. If desired, the apparatus may be constructed so that actuation of the button 27 also insures that the record 20 is moving as long as the drive wheel 31 is in contact therewith. In Figure 2, this result is accomplished by means of the switch contacts 16 and 17, which are in circuit through the electrical lead wires 18 and 19 in parallel with the usual stop-go switch on the microphone handle. Depressing the button 27 causes the head thereof to close contact 17 against contact 16, thereby causing the record 20 to turn.

As the marking wheel 21 rolls over the record 20, it impresses a series of spaced indentations 38 upon the surface thereof (Figure 4). The marking wheel 21 is spaced from the stylus 36 along the spiral trajectory traced by the relative movement of said stylus 36 and the record 20. Hence, when actuated, said marking wheel 21 falls into the sound groove of the recording. The position of the marking wheel 21 may be adjusted nicely by moving the bracket 25 relative to the frame 41 of the dictating machine, as is facilitated by the cooperating slots 42 and the securing bolts 43. The distance between the stylus 36 and the marking wheel 21 is set at any convenient distance, say a length of sound track containing ten to twenty words. By re-setting the bracket 25, the marking wheel 21 may be moved one or more additional grooves away from the stylus 36, thereby increasing the time interval between the signal and the spoken matter to which it relates.

If during dictation, the speaker realizes that he has misspoken, he simply actuates the marking apparatus, thereby impressing the warning signal upon a portion of the already cut sound

track, which signal accordingly will be heard before the error which it is desired to correct. He then dictates the correction.

The procedure in editing is about the same. If the dictator hears an error when playing back his dictation, he actuates the marking apparatus, thereby superposing the warning signal upon a portion of the sound track which precedes the portion thereof in contact with the playback stylus. He may then write the correction on the paper log sheet, or on a note to the stenographer. Or he may set the machine for dictating at the end of the cut sound groove, and dictate the correction or insert. He then sets the machine for listening and adjusts it to play back the last correction signal, which prevents him from failing to edit any of the recording. The stenographer of course hears the signal before she hears the text which she is required to alter to conform to the editing.

Figures 6-9 illustrate a second embodiment of my invention, which embodiment is capable of impressing a complete warning signal upon the record while the latter is at rest, and also while the latter is moving. In this embodiment, the reciprocating marking arm 44 is pivoted to the bracket 45 and has a guide slot 46 in which the sliding block 47 is reciprocated by the eccentric pin 48. Said eccentric 48 is fixed to the friction drive wheel 49, which in turn is driven by frictional engagement with the record 20. Said wheel 49 is journaled upon the shaft 50 carried on one end of the yoke 51. The other end of the yoke 51 is pivotably secured to the bracket 45. The yoke 51, like the yoke 23 of Figure 1, is spring-loaded by a spring 26 and is shown deflected against this spring loading by the member 29, which member is depressed through operation of the Bowden wire 28. When said Bowden wire 28 is released, the spring 26 lifts the yoke 51 upward, thereby lifting the eccentric 48, and through it, pivoting the marking member 44 out of contact with the record 20. When the member 44 is thus lifted, its weight acts upon the eccentric 48 to cause the friction wheel 49 to rotate until said eccentric 48 is at its lowest point. Consequently, the marking member is in position to mark upon the record 20 whenever the yoke 51 is moved down. The drive wheel 49 also serves to limit the downward movement of the member 44, thereby controlling the depth of penetration of the marking elements 52 into the surface of the record 20. If desired, a stop such as the micrometer screw 30 of Figure 1, may be provided in addition.

As best shown in Figure 9, the marking elements 52 preferably are grouped along a curve, to compensate for the varying curvature of the spiral sound track on the record 20. Thus, for example, I have found that as many as nine of the elements 52, each having a cutting width of 0.0025 inch or less, when spaced at intervals of $\frac{1}{2}$ inch and arranged on an arc of $2\frac{1}{2}$ inches, mark within the area of a single groove everywhere on a commercial record having an inner radius of $1\frac{3}{4}$ inches and an outer radius of $4\frac{1}{2}$ inches, and in which grooves are spaced as close as 280 to the inch.

Cylindrical records and endless belt records do not present this problem, since they are inscribed with a helical sound track which is uniformly curved from beginning to end. Dictating machines using such records are provided with marking members 44 wherein the scribing elements 52 are arranged along the trajectory of the

helix assumed by the sound track when the record cylinder or belt is in the machine. In other words, the scribing elements 52 are placed in a straight line, but the elements vary in length, so that all simultaneously engage the cylindrical surface of the record.

As in the case of the embodiment of Figures 1-5, that of Figures 6-9 may be actuated to index upon the record 20 by depressing the Bowden wire 28. As the yoke 51 carries the drive wheel 49 downwardly, the elements 52 engage and mark upon the surface of the record 20, regardless whether said record is or is not turning. If the record 20 is stationary, then a single trace 53 (Figure 7) is impressed upon the record 20 by actuating the Bowden wire 28. If the record is rotating and translating laterally, in the manner indicated by the directional arrows of Figure 7, then the drive wheel 49 revolves as long as it is held in frictional contact with the surface of the record 20. Each complete revolution of the drive wheel 49 reciprocates the marking arm 44 once, and thus impresses upon the record 20 one set of indentations comprising a single trace 53. If the operator chooses to place but a single trace upon the record, then he releases the Bowden wire 28 immediately upon depressing it, so that the yoke 51 and the marking arm 44 move away from the record 20 before the wheel 49 can make one complete revolution. If the operator desires to impress a series of spaced apart signals on the record 20, then he holds the Bowden wire 28 in depressed position until the drive wheel 49 has revolved for the desired interval of time.

As best shown in Figure 9, the elements 52 are preferably formed with a chisel-shaped point so that each trace 53 (Figure 7) comprises a plurality of separate V-shaped notches, which create a short, rasp-like sound upon transcription. As demonstrated above, the elements 52 may be grouped so that each trace 53 is contained wholly within a single groove of the sound track. Thus, upon transcription of the record 20, the signal does not carry over into adjacent grooves and is heard at precisely the moment intended. Further, as in the case of the embodiment of Figures 1-5, the bracket 45 may be moved relative to the frame 41 (and hence the stylus 36) by means of the cooperating slots 42 and securing bolts 43 and in that way the interval of time between hearing the signal and that portion of the record 20 to which it relates may be adjusted. At the same time, the spacing between successive traces may be varied by changing the diameter of the drive wheel 49 proportionally.

Figures 10-12 illustrate a third embodiment of my invention which is capable of placing a signal of predetermined time duration upon the sound track of a record each time an electrical switch button 60a (Figure 12) is pressed. The marking apparatus comprising this embodiment is secured to the recording and/or reproducing unit 54 carried by a traveling arm 55 of the dictating machine, which for purposes of illustration is shown to be of the type wherein a stylus 58 moves laterally across a barrel-type record 51. The marker 56 which places the signal producing marks upon the record 51, is shown as being spaced in front and to the side of the stylus 58, and forms the reciprocating element of an electrical interrupter mechanism 59.

Referring now to Figure 12, the interrupter mechanism 59 includes a cantilever spring 61, to the free end of which the marker 56 is attached, and a solenoid 62 which is electrically coupled to the leads 65, 65 through the contacts 63, 63 and the anchored end portion of the cantilever spring 61. The leads 65, 65 can be carried within the traveling arm 55, along with the usual wiring required for operation of the unit 54, and are connected to a supply of electrical energy through switch 60.

coupled to the leads 65, 65 through the contacts 63, 63 and the anchored end portion of the cantilever spring 61. The leads 65, 65 can be carried within the traveling arm 55, along with the usual wiring required for operation of the unit 54, and are connected to a supply of electrical energy through switch 60.

To mark upon the record 51, the dictator presses the button 60a, thereby closing the switch 60 and energizing the solenoid 62. Upon being energized, the solenoid 62 repels the free end of the cantilever spring 61, causing the marker 56 to reciprocate downwardly. Downward deflection of the spring 61 separates the lower contact 63 from the upper contact 63, however. This interrupts the circuit, de-energizes the solenoid 62, and permits the spring 61 to return to its null position. Because of inertia effects, however, the spring 61 and its associated marker 56 continue to move downwardly for an instant even after the circuit is broken, so that the marker 56 penetrates the surface of the record 51. Immediately thereafter the restoring force of the spring 61 acts to lift the marker 56 away from the record 51. In so doing, however, the contacts 63, 63 close and the solenoid 62 is again energized, whereupon the foregoing cycle repeats itself.

Since the marker 56 shown in Figures 10-12, is adapted to impress only a single mark in the record 51 for each reciprocation of the spring 61, it is necessary that the record 51 move beneath the unit 54 if a series of such marks is to be placed upon the record surface. The spacing between successive impressions in the record surface will then be determined by (1) the velocity with which the record surface moves relative to the marker 56, and (2) the frequency with which the marker 56 reciprocates, which in turn is determined by such factors as the physical dimensions and arrangement of the elements comprising the interrupter mechanism 59, their electrical characteristics, etc. In practice, however, it is easy to obtain a desirable spacing between successive marks, e. g. $\frac{1}{2}$ inch where the linear velocity of the record surface is of the order of 300 or 400 inches per minute. To insure that the record 51 is turning whenever the button 60a is depressed, an arrangement similar to that of Figure 2 may be used to advantage, viz., a circuit in parallel with the customary stop-go switch of the dictating machine is closed through the leads 18 and 19 upon closing the switch 60.

Advantageously, the switch 60 may be placed on the hand microphone customarily used with dictating machines, as in Figure 2, or in any other place convenient and accessible to the dictator.

At the same time, it is often desirable to control automatically and precisely the length of the signal. To this end, I incorporate a timer 64 into the electrical circuit (Figure 12), which timer 64 automatically de-energizes the mechanism a predetermined period of time after closing of the switch 60. Thus, for example, in one form the timer 64 could be combined with a signalling device which would sound or otherwise notify the dictator after the predetermined period of time has elapsed, whereupon the dictator can release the button 60a. At the same time, if desired, a signal of shorter time duration can be impressed upon the record 20, by releasing the button 60a accordingly.

A fourth embodiment of my invention, shown in Figure 13, is characterized by the ability to

place a complete indexing signal upon a record upon closing a switch, whether the record be turning or stationary. This embodiment is particularly well suited for use with dictating machines wherein a record 74 revolves about a fixed center spindle 75. An exemplary type of dictating machine embodying this general type of construction is shown in detail in Thompson et al., Patent No. 2,240,321, issued April 29, 1941, and entitled Transcribing Machines. In this application of my invention, a marking member 67 is carried by the recording and/or reproducing unit 68 (shown in dotted outline), and is provided with a plurality of marking elements 82 similar in their form and arrangement to the marking elements 52 of Figure 9, i. e., the trace which they produce falls within the area of a single groove throughout the entire recording area of the record 74.

To cause the marking member 67 to reciprocate downwardly and mark upon the record 74, the dictator closes the push-pull switch 71, thereby energizing the solenoid coil 69, through the circuit 70. This results in the marking member 67 being deflected downward, against the restraint of the spring 72. In addition to coil 69, the circuit 70 includes a solenoid-actuated switch 73, which is normally closed, as shown.

As the member 67 moves downwardly, however, the contact member 76 carried by it bridges the contacts 77 and 78 of the circuit 79, whereupon the normally open solenoid-actuated switch 80 is closed. As a result, the circuit 81 is energized, the switch 73 is opened, and the circuit 70, including the coil 69, is de-energized. Upon removal of the repelling force of the coil 69, the spring 72 returns the member 67 to the position shown in Figure 13. Before the spring can arrest the momentum imparted to the member 67 by the coil 69, the member 67 travels downwardly a distance sufficient to cause the marking elements 82 to engage the record 74 and mark upon the same.

To prevent further reciprocation of the marking member 67 unless the switch 71 is first released and then reclosed, I prefer to insert a shunt 83 across the circuit 79 in the manner shown. Said shunt 83 normally is open, due to the null position of the solenoid-actuated switch 84 connected in series with circuit 81. Upon closing the switch 80, however, as a result of bridging the contacts 77 and 78, switch 84 is closed. Consequently, that portion of the circuit 79 which contains the contacts 77 and 78 is effectively shorted out, and the switch 73 is held in the open position until such time as the switch 71 is opened and the switch 80 is de-energized. Therefore, even though the marking member 67 is in the disengaged position, the coil 69 cannot be energized until the dictator releases the switch 71.

In Figures 14-18, I show a fifth embodiment of my invention which is capable of placing on a record 20, a trace 85 (Figure 16) consisting of a predetermined member of evenly spaced surface indentations. In this case, novel mechanical timing means are provided, which regulate the deflection of the marking member 86 and the pair of marking elements 87, 88 carried thereby. As best shown in Figure 14, the marking member 86 is secured to a cantilever spring 88 anchored in the frame member 89. In addition to supporting and guiding the marker 86, the spring 88 acts as a pawl for limiting the ratchet wheel 90 to clockwise rotation. As the wheel 90 turns

in this direction, successive teeth engage and deflect the spring 88, causing the marking elements 87, 88 to reciprocate and mark upon the record 20. To obtain the trace, 85, the record 20 must of course move relative to the member 86 as the latter reciprocates. By causing the ratchet wheel 90 to rotate through an arc of predetermined length, so that the same number of ratchet teeth engage and deflect the spring 88 each time the mechanism is actuated, it follows that a trace 85 is obtained which consists of a predetermined number of surface indentations.

Referring now to Figures 14 and 15, a lever 91 is supported rotatively on the shaft 92 and includes an arm 93 extending downwardly therefrom. The projecting lip 94 on the arm 93 engages a detent 95, secured to the lever 96. Said lever 96 pivots concentric with the wheel 90 on the shaft 97, and carries a pawl 98 which is spring loaded by the leaf spring 99 so as to bear against said wheel 90. Rotation of the lever 96 in a counterclockwise direction causes the pawl 98 to move over the periphery of the wheel 90. However, clockwise rotation of the lever 96 causes the ratchet wheel 90 to rotate in the same direction, since the pawl 98 in this case is locked to the wheel 90.

To place a signal on the record 20, the dictator presses downwardly upon the key 91a. This acts to move the lever 91 counterclockwise and therefore depresses the lever 96, thereby cocking the spring 100 and stroking the piston 101 of the dashpot 102. The dashpot 102 is constructed so as to offer no resistance to movement of the lever 96 in this direction, and may include a check valve (not shown) for this purpose. Because the levers 91 and 96 pivot about different axes of rotation, the lip 94 of the arm 93 slips over the detent 95 and permits the lever 91 to carry past the lever 96, when said levers reach the position shown in Figure 17. As soon as this occurs, the tensioned spring 100 immediately acts to pivot the lever 96 in a clockwise direction, turning the wheel 90 with it. Because of the damping action in the dashpot 102, however, this rate of rotation is regulated, so that the marker 86 reciprocates at a rate which provides the desired spacing between successive indentations comprising the trace 85.

To stop the upward movement of the lever 96 upon reaching the null position of Figure 14, I provide a stop 103. Advantageously, the stop 103 may also be utilized to limit the downward deflection of the lever 91 (Figure 17).

When the lever 91 is finally released by the dictator, the spring 104, which may be considerably weaker than spring 100, carries the lever 91 in a clockwise direction. As the lip 94 contacts the lower projecting edge of the detent 95, it rotates the detent 95 into the position shown in dotted outline in Figure 18, thereby permitting the arm 93 to slip past the lever 96. The spring 105 then returns the detent 95 to its normal position, so that the mechanism is again in a position to repeat the foregoing cycle when the lever 91 is depressed again.

A sixth embodiment of my invention is illustrated in Figures 19-21, in combination with a dictating machine of the type which records upon a flexible endless belt 106 fabricated from such materials as ethyl-cellulose plastic. As best shown in Figure 20, the belt 106 is stretched over and driven by the mandrels 107 and 108 extending from the frame 109 of the dictating machine. The recording unit 110 and the reproducing unit

111 are carried by the carriage 112, the latter being supported by the guide rails 113 and 114 and driven laterally across the belt 106, in the direction indicated by the directional arrow of Figure 19, through turning of the lead screw 115. Extending from the frame 109 and lying between the inner surface of the belt 106 is a platform 116, from which a pair of pedestals 117 and 118 project upwardly (Figure 20). The pedestals 117 and 118 support the backing plates 119 and 120, respectively, the plate 119 in turn supporting the belt 107 beneath the stylus 121 of the recording unit 110, while the plate 120 supports the belt 106 beneath the stylus 122 of the reproducer unit 111. To move the recording unit 110 into position so that the stylus 121 engages the belt 106, the operator moves the key 123 downwardly. Other control means (not shown), cause the mandrels 107 and 108 to turn and thus drive the belt 106, whereupon the stylus 121 embosses a groove 124 in said belt. To position the reproducer unit 111 for playing back the intelligence recorded on the belt 106, the operator moves the key 123 upwardly.

To index a portion of the recorded area upon the belt 106 so that upon transcription of said record a warning signal is heard prior to reaching said portion, the dictator depresses the finger tab 125. This forces the L-shaped arm 126 of the bell crank 127 to swing upwardly about the pin 128. The lever arm 130 of the bell crank 131, which turns on the pin 132, is pivotably coupled to the L-shaped arm 126 by the coupling pin 133, and therefore also moves upwardly within the well 129 of the carriage 112 when the finger tab 125 is depressed. As a consequence, the lever arm 134 of the bell crank 131 rotates in a counter-clockwise direction, carrying the marking device downwardly into engagement with the upper, outer surface of the belt 106.

As best shown in Figure 21, the marking device, like that of Figures 1-5, is adapted to be actuated by the moving surface of the recording medium, and includes a multi-tooth marking wheel 135 secured to the shaft 136 and concentric with the friction drive wheel 137. Said wheel 137 limits the downward travel of the marking wheel 135, to obtain the proper amount of penetration of the teeth of the wheel 135 into the belt 106. The drive wheel 137 revolves as it frictionally engages the surface of the belt 106, causing the marking wheel 135 to roll along the belt 106 and impress therein a series of surface indentations comprising the trace 138 (Figure 19). As is the case in each embodiment of my invention described herein, said trace 138 is placed on the sound track behind the point at which the stylus engages the recording medium. A backing roll 139 is positioned beneath and supports belt 106 as the marking wheel 135 is moved into contact therewith. The roll 139 in turn is carried by the shaft 140 journaled in the pedestal 141 (Figure 20).

As long as the operator holds down the finger tab 125, and the belt 106 is turning, the marking wheel 135 continues to mark upon said belt 106. To insure that the belt 106 is turning whenever the tab 125 is depressed, mechanism similar in function to the switching means of Figure 2 can be linked to and actuated by the bell crank 131. Upon release of the finger tab 125, the marking wheel 135 moves upwardly away from the belt 106 under the influence of the tensioned spring 142, after having impressed trace 138 in said belt.

A seventh embodiment of my invention, and one which is particularly well suited to index belt-

type records, is illustrated in Figures 22-24. This embodiment has as one of its distinguishing features the capacity to place an entire trace or signal generating mark upon the belt whether said belt be moving or stationary. In this machine, a carriage 143 is supported by the guide rail 144 and carries with it a bracket 145, to which is secured the marking device. Extending downwardly from the bracket 145 is a member 148 having a slot 169 therein, along which slot 169 the block 149 translates. A link 150 is pivoted at its one end to the pin 151 extending from the block 149, and is pivotably coupled at its other end by the pin 153 to the lever 152. The lever 152 pivots on and about the pin 154 projecting laterally from the bracket 145. A spring 164 interconnects the lever 152 and the bracket 145, to resist deflection of the former in a clockwise direction.

Figure 22 shows the appearance of the various elements comprising the marking device when in the null position, i. e., the multi-tooth marking wheel 155 is disengaged from the surface of the belt 156. As best shown in Figures 23 and 24, the marking wheel 155 and the friction driving wheel 157 are keyed to and rotate with the shaft 158 journaled in the yoke 159. The yoke 159 is secured to the block 160, which block is dovetailed to the block 149 and slidable therealong. A spring 161 interconnects the block 149 and the bracket 162 extending from the slidable block 160.

To index a signal generating mark upon the belt 156, the operator depresses the finger tab 163, thereby causing the lever 152 to deflect against the restraining action of the spring 164. This movement causes clockwise rotation of the pin 153 and translates the link 150 upwardly, thus displacing the block 149 upwardly along the slotted member 148. As the driving wheel 157 rises a small distance, it engages the surface of the belt 156, due to the narrowing clearance between the surface of the belt 156 and the line of action of the slotted member 148. As a result, the driving wheel 157 commences to turn, thus driving the marking wheel 155 and causing the teeth of the latter to penetrate and mark upon the surface of the belt 156. As the clearance between the belt 156 and the slotted member 148 continues to decrease, the block 160 commences to slide relative to the block 149 and away from the belt 156, thereby tensioning the spring 161. As the driving wheel 157 rises above the horizontal center line of the mandrel 165, however, and the clearance between the belt 156 and the slotted member 148 begins to increase, the spring 161 acts to drive the driving wheel 157 inwardly, and hold it firmly against the surface of the belt 156. At the end of the full stroke of the lever 152, which is limited by the stop 166, the marking wheel 155 is disengaged completely from the surface of the belt 156.

Upon releasing the finger tab 163, the spring 164 reacts to return the block 149 and its associated mechanism to the null position of Figure 22, which results in the marking wheel 155 retracting the mechanical movement described above. If, during the time the marking wheel 155 remains in the uppermost position, the belt 156 has remained stationary, then, during the return stroke, the marking wheel 155 at most places additional marks in the belt 156 without increasing the time duration of the index signal. If, on the other hand, the belt 156 has moved, then the downward movement of the marking wheel 155 either acts to make a single signal of longer

time duration, or else places an additional separate signal upon the belt 156 which is spaced from the first signal, depending upon the length of time the marking device is held in the uppermost position.

In any case, the marking wheel 155 places an audible indexing signal upon the sound track 167 which is spaced to the left of the stylus 168, as viewed in Figure 23. Moreover, the cooperating slots 147 and retaining screws 146, which fasten the bracket 145 to the carriage 143, provide means for adjusting the position of the marking wheel 155 to mark in different grooves of the sound track 167, thereby varying the time interval between hearing the alerting signal and hearing the corresponding recorded intelligence which has been edited by the dictator.

Thus, I have shown and described various embodiments of my invention which teach the utility and novelty of my novel method and which fulfill the above recited objects. By way of showing the versatility of my invention, I have shown that it can be adapted for use with diverse types of dictating machines, both as to the form of recording medium used and the manner in which the medium is recorded upon. In addition, I have disclosed methods of an apparatus for obtaining signals of predetermined length and of varying tonal characteristics. Also, I have disclosed marking apparatus which operates both on direct mechanical actuation and remotely through electrical actuation.

While I have shown and described several embodiments of my invention for practicing my novel method, it will be apparent to those skilled in the art that the embodiments disclosed herein are exemplary only and that various changes and rearrangements of the details shown herein may be made without departing from the spirit of the invention, the scope of which is defined in the appended claims.

I claim:

1. In sound translating apparatus including means for supporting and driving a recording medium, a carriage movable across said medium, and a recording unit carried by said carriage and including a stylus adapted to generate a sound impressed track in said medium, mechanism for impressing an audible signal made up of discretely spaced surface indentations on said generated sound track for the purpose of alerting a transcriber to subsequently following sound track conditions, said mechanism comprising: a bracket member extending from said carriage, a lever pivoted on said bracket member, spring means resisting deflection of said lever, a first member secured to said bracket member and positioned adjacent a portion of said recording medium, said first member having an elongated slot therein the intermediate portion of which is closer to the surface of said recording medium than the end portions thereof, a second member movable along said slot, means drivably coupling said second member to said lever, a shaft rotatably secured to said second member, a drive wheel and a circular member on said shaft, and a plurality of marking elements spaced on the periphery of said circular member, whereby deflecting said lever moves said drive wheel across said recording medium and turns said circular member, said circular member being spaced from said stylus to cause said marking elements to mark upon said sound track in advance of said portion thereof.

2. In sound translating apparatus including

means for supporting and driving a recording medium, at least a portion of said medium having a substantially cylindrical configuration when supported by said means, a carriage movable across said medium, and a recording unit carried by said carriage and including a stylus adapted to generate a sound track in said medium, means for manually superimposing upon said generated sound track a coexistent separately audible signal for alerting a transcriber to subsequent material upon said sound track, said superimposing means comprising: a bracket projecting from said carriage and positioned adjacent to said cylindrical portion of said medium, said bracket having a substantially straight guide slot therein, the line of action of said guide slot at the intermediate portion thereof being closer to the surface of said medium than at the end portions thereof; a member constrained to move along said guide slot; lever means for moving said member along said guide slot; a block slidably paired to said member for movement toward said medium substantially perpendicular to the line of action of said guide slot; spring means urging said block toward said medium whereby said block is movable relative to said member to adjust for the changing distance between said guide slot and said medium as said member moves along said intermediate portion of said slot; a toothed marking wheel rotatably secured to said block; said wheel out of contact with said medium when said wheel is positioned at either of said end portions of said guide slot, and positioned to mark upon said medium when said wheel is at said intermediate portion of said guide slot; and means for turning said marking wheel upon contact with said medium, said wheel being spaced from said stylus to mark upon said sound track in advance of said preselected portion thereof.

3. In sound translating apparatus including mechanism for supporting and driving a recording medium, at least a portion of said medium having a substantially cylindrical configuration when supported by said mechanism, a carriage movable across said medium, and a recording unit carried by said carriage and including a stylus adapted to generate a sound track in said medium, means for producing a coexistent separately audible signal on said medium superimposed upon said sound track at a location prior in time sequence to the material to which said signal relates, said producing means comprising: a bracket portion projecting from said carriage and positioned adjacent to said cylindrical portion of said medium, guide means on said bracket portion the line of action of which is substantially tangential to said cylindrical portion of said recording medium, a member constrained to move along said guide means, lever means for moving said member along said guide means, a substantially circular member rotatably secured to said second member and including a plurality of marking elements spaced on the periphery thereof, said circular member positioned to intercept the surface of said recording medium upon movement of said member along said guide means tangential to said medium, and means for turning said circular member upon contact with said medium, said circular member being spaced from said stylus to cause said marking elements to mark upon said sound track at a position reproducible previous to said preselected portion of said sound track.

4. In sound translating apparatus including means for supporting and driving a sound recording medium, a recording unit, and means for moving said recording unit and said recording medium relative to each other, means for imposing the trace of an audible signal on a portion of said recording medium, said last mentioned means comprising: a bracket member connected to said recording unit, a rotary member including a plurality of marking elements positioned thereon, said rotary member normally out of contact with said recording medium but movable relative to said bracket member in a path which brings said marking elements into wiping engagement with said recording medium, means constraining said rotary member to movement along said path, means for moving said rotary member along said path, and drive means for turning said rotary member upon engagement of said marking elements with said recording medium, whereby said marking elements successively mark upon said recording medium to indent therein a trace of an audible signal.

5. In sound translating apparatus including means for supporting and driving a sound recording medium, a carriage, means for moving

said carriage and said recording medium relative to each other, and a recording unit secured to each carriage, means for imposing the trace of an audible signal on a portion of said recording medium, said last mentioned means comprising: a toothed marking wheel carried by said carriage and movable in a path the locus of which brings said marking wheel into rolling contact with said recording medium during only a portion of its travel along said path, means constraining said marking wheel to movement along said path, and means for moving said marking wheel along said path.

ALBERT I. KEGAN.
